Attorney

UNITED STATES PATENT OFFICE.

WILLIAM SVEJKOVSKY, OF OKLAHOMA CITY, OKLAHOMA.

CORNCUTTER.

Application filed May 24, 1921. Serial No. 472,299.

To all whom it may concern:

Be it known that I, WILLIAM SVEJKOVSKY, a citizen of the United States, residing at Oklahoma City, in the county and State of Oklahoma, have invented certain new and useful Improvements in Corncutters, of which the following is a specification.

This invention relates to a corn cutter and more particularly to a device of that character that is applied to the hand of the operator whereby it will be actuated upon the closing of the hand.

The main object of the invention is to provide a corn cutter having a fixed guard and blade carried adjacent the hand of the operator and a knife having one end arranged adjacent the end of the operator's fingers and its other end slidably and pivotally mounted on the guard and blade whereby when the hand of the operator is closed, the knife will be given both a sliding and rocking action with respect to the guard and blade so as to facilitate the cutting of kafir corn and the like.

A further object of the invention is to provide a device of the above character that is simple in construction, strong and durable and which it is believed may be manufactured at a reasonably low cost.

Various other objects and advantages of my invention will become apparent during the continuance of the following description.

In the drawings:—

Figure 1 is a view in top plan of my invention showing the same applied to the hand.

Figure 2 is a view in side elevation.

Figure 3 is a view in transverse cross section taken on line 3—3 of Figure 1.

My invention consists generally in a metallic guard 10 that is substantially U shaped when viewed in cross section and as seen in Figure 3, adapted to fit the hand of the operator in the manner shown in Figure 1. Inasmuch as this is only the preferred form of guard it is to be understood that I do not limit myself to any size or dimension nor to the material used in the construction thereof. The guard carries retaining straps 11 and 12, one of which fits about the palm of the hand while the other encircles the wrist of the operator as shown in Figure 1. This construction renders the guard quickly detachable to or from the hand of the operator and yet insures it being held firmly in place when the cutter is in operation.

A metallic blade 13 is connected to the guard 10 as at 14 and is so arranged whereby it lies along one side of the palm of the hand and at right angles to the general extent thereof.

In other words when the hand is held in a horizontal position, the blade 13 will assume a vertical position. Certain edges of the blade may or may not be sharpened to a fine degree, this being left to the discretion of the operator and being somewhat dependent upon the nature of the material desired to be cut.

Adjacent its forward end yet spaced from the edges thereof, the blade 13 carries a projecting pin 15, the purpose of which will be hereinafter described.

A knife blade 16 is also provided which is elongated and slightly curved when viewed in plan as shown in Figure 2. At one end, 75 the blade is carried on a strap or other securing member 17 which is adapted to encircle the fingers of the operator as clearly shown in Figure 1 and intermediate its ends it is provided with an elongated slot 18 which receives the pin 15 of the blade 13. In order to hold the blade in place, suitable means such as shown at 19 may be positioned on the pin 15.

From the above construction it will be observed that when the hand of the operator is closed both a sliding and pivotal action will be imparted to the knife blade 16 which will cause the same to both slide and rock with respect to the blade 13 such as will produce an efficient cutting action. When the hand of the operator is open, the blade will of course move to its normal position.

From the foregoing it is believed that the advantages and novel features of my invention will be readily understood and therefore further detailed description is deemed unnecessary.

What is claimed is:—

A corn cutter comprising, in combination, 100 a metallic guard substantially U shaped when viewed in cross section, adapted to fit the hand of the operator, a pair of retaining straps, one of which is adapted to fit to the palm of the hand while the other encircles the wrist, a metallic blade connected to the guard and arranged to lie along one side of the palm of the hand and at right

22
angles to the general extent whereby it will assume a vertical position when the hand is held in a horizontal position, a projecting pin provided adjacent the forward end of the said metallic blade and spaced from the edges of the latter, a knife blade provided intermediate its ends with an elongated slot to receive the projecting pin of the said me-

tallic blade, means engaging the pin for holding the knife blade in place, and a securing strap having adjustment to one end of the said knife blade and being adapted to encircle the fingers of the hand. 10

In testimony whereof affix signature.

WILLIAM SVEJKOVSKY.
